UNITED STATES PATENT OFFICE.

ADOLF VOLLM, OF SOMERVILLE, MASSACHUSETTS.

GLASS CUTTER.

Application filed March 12, 1928. Serial No. 261,118.

The invention relates to improvements in glass cutters of the type provided with a cutting wheel at the lower end of a shank. It is now customary, when the wheel is badly 5 worn, to discard the entire cutter, but it is the aim of my invention to provide an improved construction in which the wheel is demountably carried by the lower end of the shank, may be readily removed, and replaced 10 with a new wheel, thus permitting the shank and the wheel-retaining means of one cutter to last indefinitely, with only the necessity of renewing the cutting wheel from time to time, with an expense which is negligible.

15 With the foregoing in view, the invention resides in the novel subject matter herein-after described and claimed, description being accomplished by reference to the accompanying drawing.

20 Fig. 1 is a side elevation and Fig. 2 a front elevation of a glass cutter embodying my improvements.

Fig. 3 is an enlarged vertical sectional view on line 3—3 of Fig. 2.

25 Fig. 4 is an enlarged lower end view.

Fig. 5 is a transverse section on line 5—5 of Fig. 3.

30 Figs. 6 and 7 are perspective views of the block which is instrumental in holding the cutting wheel detachably in place.

Fig. 8 is a perspective view of a stamped metal block or plate which may if desired be used in place of that shown in Figs. 6 and 7.

35 The shank 8 of the cutter herein disclosed, is of the construction shown in my pending U. S. application Serial No. 235,722, filed November 25, 1927, with the exception of the improved construction at the lower end 40 of said shank, and I wish to explain that this improved construction is usable with a shank of any form and not necessarily with the particular shank shown.

The lower end 9 of the shank 8 is inclined somewhat more steeply than usual and 45 is provided in its front corner with a receiving groove or notch 10 for a cutting wheel 11. Leading rearwardly from this groove, the shank end 9 is also provided with an 50 additional groove 12 for a purpose to appear, and a screw-receiving socket 13 is formed in the shank, registering with said groove 12. At opposite sides of the groove or notch 10, the lower end 9 of the shank 8 55 is formed with recesses 14 to receive the

shaft or pin 15 of the wheel 11, or possibly integral trunnions on said wheel, and it is to be understood that the term "shaft" used in claiming the invention is to be considered as comprehending either of these constructions, as they are mechanically equivalent.

A clamping block 16 of forwardly tapered form, contacts with the lower end 9 of the shank 8 and is provided at its front end with a wheel-receiving slot 17 which registers with the groove or notch 10. The rear portion of this block is formed with a countersunk opening 18, a screw 19 passes through this opening and is threaded into the socket 13, and ribs 20 are formed on the block 16 for reception in the groove 12, holding the block against turning about the screw. While it will be understood that both the block and the shank could be recessed to jointly receive the shaft 15, the block is, in the present showing, free from such recessing and merely holds the shaft tightly in the recesses 14. Moreover, while the block is shown contacting only at its rear end with the lower end 9 of the shank 8, it is 80 obvious that it might contact throughout a greater part of or in fact its whole length. By the construction shown however, tightening of the screw 19 swings the front end of the block 16 toward the lower end of the shank 8 and hence produces probably a more effective clamping means for the shaft 15 than if some other arrangement were employed.

Fig. 8 discloses a stamped metal block or plate which may be used in place of the block 16. This block or plate 16' is formed with a slot 17' at its front end with a screw-receiving opening 18', and at its rear end with an upwardly stamped lug 20'. The wheel 11 is receivable in the slot 17', the screw 19 is receivable in the opening 18', and the lug 20' is adapted for reception in the rear portion of the groove 12.

The construction shown and described is 90 simple and inexpensive, may be easily and advantageously manufactured and sold at small cost, and permits quick and easy interchange of cutters. By merely loosening the screw 19 sufficiently to permit the shaft 15 to pass out of the recesses 14, the wheel 11 95 may be detached when badly worn. Then another wheel may be inserted with equal ease and will be held in proper position upon tightening of the screw.

I claim:

1. In a glass cutter, a shank having a lower edge at an acute angle to its front edge, said shank being formed with a wheel-receiving groove which opens through both of said edges, a clamping block contacting with said lower edge of said shank and having a wheel-receiving slot registering with said groove, a cutter wheel in said groove and slot having a shaft disposed between said lower edges of the shank and said block, at least one of these members being recessed to receive said shaft, and a screw passing through said block and threaded into said shank for detachably securing the former to the latter.

2. In a glass cutter, a shank having a lower edge at an acute angle to its front

edge, said shank being formed with a wheel-receiving groove which opens through both 20 of said edges, a clamping block contacting with said lower edge of said shank and having a wheel-receiving slot registering with said groove, a cutter wheel in said groove and slot having a shaft disposed between 25 said lower edges of the shank and said block, at least one of these members being recessed to receive said shaft, and a screw passing through said block and threaded into the lower end of said shank to detachably secure 30 the block to the shank, said block having a longitudinal rib received in said groove preventing turning of the block about the screw.

In testimony whereof I have hereunto affixed my signature.

ADOLF VOLLM.
